UNITED STATES PATENT OFFICE

2,288,720

BOX-MAKING MACHINE

Cutler D. Knowlton, Beverly, Mass., assignor to
 Hoague-Sprague Corporation, Lynn, Mass., a
 corporation of Massachusetts

Application April 5, 1940, Serial No. 328,061

12 Claims. (Cl. 91—50)

The present invention relates to a machine for applying an adhesive, for example, glue, to box blanks, of the type fully disclosed in United States Letters Patent No. 2,186,977, granted January 16, 1940, on an application filed in my name, and is directed particularly to an improved construction thereof adapted to protect the glue used therein from the drying influence of the air.

In the manufacture of boxes as accomplished by the machine of the aforesaid United States Letters Patent a very rapid drying glue is employed in order to insure proper adhesion of the end-wings of the box to the corner-laps during the short time the operator holds the box in contact with the box-forming elements of the machine. Because of the quick-drying properties of the glue, it dries rapidly on the applying rolls and accumulates thereon in a very short time to such an extent that the machine is rendered inoperative.

It is an object of the present invention to modify the aforesaid machine in such a manner that the glue carrying rolls and the means for supplying glue thereto are substantially protected from exposure to air.

The glue is applied to the end-wings of the illustrated box by a glue roll which is supplied with a quantity of glue in excess of that required from a glue receptacle, the amount carried by the roll being governed by a co-operating doctor roll. A feature of the invention resides in means for returning the excess glue to the glue receptacle while protecting the glue from the air, and this is effected in the present machine by enclosing the doctor roll and the lower portion of the applying roll in a housing, the housing being arranged to extend from the lower side of the doctor roll to the glue receptacle whereby the excess glue is drained back to the glue receptacle.

Further features of the invention reside in means for supporting the applying roll from one end only so that the box blank may be held close to that end without the interference of a projecting shaft or bearing therefor, in means for supplying the glue to the rolls which, as illustrated herein, is accomplished by delivering the glue through a nozzle, the open end of which is inclined toward the surface of the doctor roll close to the bite of the rolls so as to project the glue onto the surface of the doctor roll substantially at the bite of the rolls and midway between their ends, whereby the doctor roll carries the glue into contact with the applying

roll, and in a guide close to the end face of the applying roll for guiding the end-wing of the box.

The glue receptacle employed in this machine is a bottle, the mouth of which is held in contact with the return end of the extension of the aforesaid housing. When the glue is exhausted from the glue bottle, it is necessary to refill the bottle, and another feature of the invention resides in a quick release clamp arranged to hold the bottle securely in place and by one movement to release it so that it may be readily removed and replaced. As illustrated herein, the aforesaid clamp comprises a horizontal arm which extends beneath the bottom of the bottle, a support for the arm, and a cam operable to raise and lower the arm.

The machine of the present invention will now be described with reference to the accompanying drawings, in which

Fig. 1 is a perspective view of the machine with the cover 72 removed;

Fig. 2 is a perspective view of a box blank;

Fig. 3 is an enlarged view, partly in section, as seen from the left end of the machine in

Fig. 1; and

Fig. 4 is an enlarged vertical section on the line IV—IV of Fig. 3.

Without describing the construction and operation of the machine as a whole, since it is adequately covered in the aforementioned patent, it is sufficient to point out that one of the instrumentalities of that machine with which the present invention is concerned is the means for applying glue to a box blank 10, illustrated in Fig. 2, having opposite side-wings 12, corner-laps 14, and end-wings 16. In the present machine, as in the patent machine, the gluing means comprises a glue applying roll 18 and a presser roll 20 co-operating therewith to hold the extended end-wing 16 of the box 10 against the glue roll. In order to hold the box in proper position, a table 22 is provided which extends along the end of the glue roll and on which the edges of the side-wings 12 of the partially formed box (Fig. 2) may be rested during the movement of the box past the unobstructed end face of the applying roll, as the end-wing 16 is passed between the glue applying roll and presser roll. The table is adjustably supported on columns 24 so that it may be raised or lowered according to the depth of the side-wings 12.

The rolls 18 and 20 are supported from one end only upon driven shafts extending from a gear casing 26 which is bolted to a base 28 supported from the floor by legs 30. The columns 24

which support the table 22 pass through the base 28 at their lower ends and are journaled at their upper ends in arms 32, the latter being fixed to posts 34 bolted to the base 28. The lower ends of the columns 24 are threaded in bearing sleeves 25 manually rotatable in the base 28 to raise or lower the table 22, as described in the patented machine. A wall 38 (Fig. 1) extends from the forward end of the table 22 along the rear edge thereof between it and the end of the glue roll, the top edge of the wall lying slightly below the top of the glue roll 18 (Fig. 3). The wall 38 serves as a guard for the corner-laps 14 and a guide for the end-wing 16 of the box as it is moved along the table 22 and is fixed by means of brackets 40 to the arms 32. The entrance of the end-wings into the space between the glue and presser rolls is facilitated by inclined guide members 42 and 44 fixed to the gear casing (Fig. 1).

In the patented machine a pick-up roll is provided, the lower portion of which dips in a glue tray for lifting glue therefrom to the surface of the applying roll. In the present machine a doctor roll 46 similar to the aforesaid pick-up roll is employed for spreading glue over the surface of the applying roll, but the glue tray has been removed and a nozzle 48 substituted therefor. The nozzle 48 is disposed adjacent to the bite of the rolls (Fig. 3) and midway between the ends of the rolls (Fig. 4) so that it delivers glue onto the upgoing surface of the roll 46 close to the bite of the rolls. In order that glue may be delivered at the most advantageous point on the doctor roll, which may vary somewhat with the viscosity of the glue, the nozzle is adjustably supported at the upper end of a pipe 50 by an elbow 52 so that its position relative to the surface of the doctor roll may be changed slightly. The lower end of the pipe 50 is threaded into the discharge side of a pump 54 and a hand operated valve 56 is interposed in the pipe between the pump and the nozzle by which the quantity of glue delivered to the nozzle may be controlled. The valve is set so that somewhat more glue than is required is delivered to the roll 46 and is carried up thereby into contact with the applying roll 18, which turns in a direction opposite to the roll 46. Since only a small part of the glue can pass between the rolls, the greater part thereof spreads laterally toward the ends of the rolls and forms an even coating over the entire surface of the roll 18, the excess glue being squeezed back so that it runs down the surface of the roll 46 and drops from the bottom thereof.

Scrapers 41, one of which is shown in Fig. 3, are provided at the ends of the rolls 18 and 46 for cleaning the glue therefrom. The scraper 41, as illustrated, constitutes a flange on the inside of a housing which will be described hereinafter, the edge of the flange being machined to substantially engage the ends of the rolls. The effective scraping surface overlaps the ends of both rolls at their bite, said surface lying on lines passing through the axes of the rolls. The lower portion 43 of the scraper extends backward to provide a convex deflector which carries the glue scraped off by the portion 41 downwardly toward the bottom of the housing. In order to relieve any pressure caused by accumulation of glue between the scrapers and the ends of the roll 46, the scrapers are cut back from the ends of the roll 46 along the convex portions 43.

Since the glue employed dries very quickly, it

is desirable to protect it from the air as much as possible and to return the excess glue to the glue supply for reuse. In the present machine, the glue is contained in a bottle 58 and is drawn therefrom through a pipe 60, one end of which extends to the bottom of the bottle and the other end of which is connected to the aforesaid pump 54 and delivered by the pump through the nozzle 48 to the bite of the rolls. In order to protect the excess glue which runs down the doctor roll 46, and that which is cleared from the ends of the rolls, from the air as much as possible, a housing 62 is provided for enclosing the doctor roll and the lower portion of the applying roll.

The housing 62 includes end walls made up of overlapping sections 64 and 66 (Fig. 3). The top and vertical edges of the walls are provided with inwardly directed flanges 68 and 70 (Fig. 1) which serve in part to form the front and the back walls and the top of the housing. The flanges 68 at the top of the end walls are extended so that they closely fit about the ends of the roll 18. The housing is completed by front and back cover plates 72 and 74 arranged to be held against the flanges 70. The walls of the housing are provided with flanges 76 at their base by which the walls are bolted to a flange 78 formed on the upper edge of a funnel-shaped hopper 80 to be hereinafter described. The front and back cover plates are provided with lugs 82 at their lower ends extending at right angles thereto adapted to rest on the flange 78 whereby these plates are supported. In order to quickly locate the plates, pins 84 are fixed in the ends of the lugs, the lower end of the pins being adapted to rest in apertures 86 formed in the flange. The rear plate 74 extends only part way up the housing (Fig. 3). The opening above the rear plate 74 is left uncovered to permit an unobstructed view of the condition existing at the bite of the rolls so that prompt adjustments may be made in the event that there is too much or too little glue being delivered to the rolls. The front plate 72 is extended upwardly above the top of the housing to a point closely adjacent to the lower guide 44, the plate 72 having inwardly extending flanges 90 which substantially enclose the front side of the applying roll. By removing either the front plate or the back plate access may be had to the glue rolls. In Fig. 1 the front plate 72 has been omitted in order to show the glue rolls. The sections 64 of the side walls have formed integral therewith the aforesaid scrapers 41. It is apparent from the construction of the housing that it can be readily disassembled, if necessary, without disturbing the glue rolls, by removing the cover plates and unbolting the side walls from the hopper.

The aforesaid funnel-shaped hopper 80 has a lower portion which extends laterally in the form of a conduit or passage 92 to a point adjacent to the mouth of the glue bottle 58. The hopper 80 is supported from its under side by a pedestal 94 bolted to the base 28, and the end of the lateral extension, which terminates in a flange 96 having ears 98 (Fig. 1) projecting therefrom, is secured by means of bolts passing through said ears over a semicircular opening formed at the edge of the base 28 so as to hold the hopper rigidly in place. The passage 92 is provided with an opening 100 (Fig. 4) in its upper wall which is covered by a plate 102 by which access may be had to the interior of the extension, and an aperture 104 is formed in the lower wall of the extension adjacent to its end

for the admission of the pipe 60 into the mouth of the bottle 58.

In order to facilitate centering the mouth of the bottle 58 with the flanged end of the extension prior to clamping the bottle in engagement therewith and to prevent damage thereto, an annular metal disk 106 (Fig. 4) having a downwardly extending flange and a corresponding underlying felt disk 108 are secured to the flange 96 by a ring 110 bolted to the flange. The bottle is held from lateral displacement by a band 112 which embraces the outer portion of the bottle and holds it in the semicircular opening formed in the base 28 (Fig. 1), the band being bolted to the base at each side of the opening. A felt lining 114 is secured to the inside of the band and to the semicircular opening to protect the bottle from accidental breakage by careless insertion or removal, and springs 116 are disposed behind the bottle to hold it firmly against the band so that it will not move with respect thereto. The bottle is supported by a horizontal arm 118 having a sleeve 120 of some soft material thereon, the arm being mounted for vertical movement whereby the bottle may be raised into contact with the felt disk 108 at the flanged end of the extension or may be lowered therefrom for replacement. Accordingly, the arm 118 is fixed to a bracket 122 which is arranged to slide vertically on a post 124, the upper end of which is fixed in an aperture formed in the base 28 by a set screw 126. A cam 128 is pivotally mounted on the bracket 122 and bears against the upper surface of a block 130 fixed to the lower end of the post 124. A handle 132 is formed integral with the cam and provides means for turning the cam so as to raise and lower the arm 118. After the arm has been lowered it must be moved radially to one side to permit the bottle to be lowered so that its neck clears the band 112. A pin 119 is passed through the post 124 with its ends projecting on opposite sides thereof far enough to limit the radial movement of the bracket 122 in either direction about the post. As located, the pin serves as a combined stop and centering means, the inner end of the pin, as seen in Fig. 4, serving to center the arm 118 beneath the flange 108.

The pump 54 is of the conventional gear type and is driven by a sprocket 134 and chain 136, the pump being bolted to the base 28.

From the description of the improved machine, it is apparent that the glue is drawn from the bottle 68 through the pipe 60 by the pump 54 and delivered from the pump through the pipe 50 to the nozzle 48. The glue projected upon the doctor roll 46 is in part distributed in an even coating over the surface of the applying roll, that part of the glue being carried above the housing into contact with the end-wing of the box while the remaining excess glue is squeezed from the bite of the rolls and runs down, together with the glue scraped from the ends of the rolls, into the funnel-shaped hopper 80. From there the glue runs down the passage 92 and into the bottle 58 so that the unused glue is returned for further use substantially unexposed to the air and, therefore, undeteriorated.

At the end of the day the machine may be quickly cleaned by removing the glue bottle and replacing it with a bottle of water. The machine is then set in operation and with the hand valve wide open the water is pumped through the nozzle over the glue rolls and flows back to the

bottle through the passage 92 of the hopper, thereby thoroughly washing all parts exposed to the glue. One or two bottles of clean water will ordinarily keep the machine free of any accumulation of glue with the minimum amount of effort on the part of the operator.

Having described my invention, what I claim as new and desire to secure by Letters Patent of the United States is:

1. In a machine for applying adhesive, such as glue, to box blanks, a glue applying roll, a doctor roll co-operating therewith to regulate the quantity of glue on said applying roll, a demountable glue receptacle remote from said rolls, means for delivering glue from the receptacle to the bite of the rolls, and means for returning the excess glue at the bite of the rolls to the glue receptacle comprising a housing enclosing the doctor roll and the lower portion of the applying roll, a portion of said housing being adapted to be connected with the glue receptacle.

2. In a machine for applying glue to box blanks, a glue applying roll, a doctor roll co-operating therewith to remove the excess glue from the applying roll, a glue receptacle, means for delivering glue in excess of that required from the receptacle to the bite of the rolls, and means for returning the excess glue at the bite of the rolls to the glue receptacle comprising a housing enclosing the doctor roll and the lower portion of the applying roll, and a downwardly extending conduit fixed to the bottom of said housing, the lower end of the conduit being adapted for clamping engagement with the glue receptacle.

3. In a machine for applying glue to box blanks, a glue applying roll, a doctor roll co-operating therewith to remove the excess glue from the applying roll, a glue receptacle, means for delivering glue in excess of that required from the receptacle to the bite of the rolls, and means for returning the excess glue at the bite of the rolls to the glue receptacle comprising a housing enclosing the doctor roll, said housing having an aperture in its top wall through which the applying roll projects and being open at the bottom, and an extension mounted at the bottom over the opening, said extension terminating adjacent to the glue receptacle and being adapted for clamping engagement therewith.

4. In a machine for applying glue to box blanks, a glue applying roll, a doctor roll co-operating therewith, a glue receptacle, means for delivering glue from the receptacle to the bite of the rolls, a housing arranged to enclose the doctor roll, a portion of the applying roll and the glue delivering means, said housing supporting said receptacle and having end walls, and flanges extending inwardly from said end walls, said flanges having edges substantially touching the ends of the applying roll and the doctor roll at their bite whereby the glue at the ends of the rolls is scraped therefrom and directed to the glue receptacle.

5. In a machine for applying glue to box blanks, a glue applying roll, means for supporting said applying roll from one end only with its top side exposed and its opposite end face unobstructed, a guide for the box blank close to said unobstructed end face of the applying roll, a doctor roll disposed below said applying roll and co-operating therewith, and a nozzle for delivering glue to the doctor roll, said nozzle being positioned adjacent to the bite of the rolls midway between their ends with its delivery end adjacent to the surface of the doctor roll in advance

of the bite of said rolls whereby the glue is deposited on the surface of the doctor roll and carried upwardly into contact with the glue applying roll.

6. In a machine for applying glue to box blanks, an applying roll, a glue receptacle comprising a bottle having a mouth, means for delivering an excess of glue to said applying roll, a conduit for returning excess glue from said roll to said bottle, and means for holding the bottle with its mouth against the end of the conduit comprising an arm extending horizontally beneath the bottom of the bottle, a bracket for supporting the arm, a spindle upon which the bracket is mounted for vertical movement, a cam pivoted to the bracket, said cam having fixed thereto an operating handle and a block fixed to the spindle, said cam bearing against the block whereby movement of the handle will raise or lower the arm.

7. In a machine for applying glue to box blanks, a glue applying roll, a doctor roll co-operating therewith, means for delivering glue to said rolls, and means for substantially enclosing the doctor roll and the lower portion of the glue applying roll comprising a hopper-shaped receptacle disposed below the doctor roll, end walls fixed to said receptacle opposite the ends of said roll, said end walls having inwardly directed flanges, and cover plates adapted to be supported at their lower edges by the hopper and to rest against the inwardly directed flanges of the end walls.

8. In a machine for applying glue to box blanks, a glue applying roll, a doctor roll disposed below said applying roll and co-operating therewith, means for delivering glue to said rolls, and means for substantially enclosing the doctor roll and that portion of the glue applying roll below its axis comprising a hopper-shaped receptacle disposed below the doctor roll, end walls mounted on said receptacle having vertical edge portions, said end walls being composed of overlapping sections independently fixed to said receptacle, each section being removable therefrom without disturbing any other section, and cover plates adapted to be supported at their lower edges by the hopper and to rest against the vertical edge portions of the end walls.

9. In a machine for applying glue to box blanks, a glue applying roll, a doctor roll disposed below said applying roll and co-operating therewith, means for delivering glue to said rolls, and means for substantially enclosing the doctor roll and that portion of the glue applying roll below its axis comprising a hopper-shaped receptacle disposed below the doctor roll, end walls,

having vertical edge portions, fixed to said receptacle opposite the ends of said rolls, and cover plates adapted to be supported at their lower edges by the hopper and to rest against the edge portions of the end walls, one of said cover plates extending above the end walls opposite the cylindrical face of the glue applying roll, said plate having inwardly directed flanges at its opposite edges overlapping the ends of the glue applying roll and partially enclosing the same.

10. In a machine for applying glue to box blanks, a glue applying roll, a doctor roll co-operating therewith, means for delivering glue to said rolls, and means for substantially enclosing the doctor roll and the lower portion of the glue applying roll comprising a hopper-shaped receptacle disposed below the doctor roll having a flange at its upper edge, end walls fixed to the flange of the receptacle opposite the ends of said roll, cover plates constructed and arranged to be held against the edge portions of the end walls, and means for supporting said cover plates comprising lugs fixed to the bottom edges of said plates, said lugs being adapted to rest on said flange, pins fixed to said lugs, and recesses formed in said flange for receiving the ends of said pins.

11. In a machine for applying glue to box blanks, a glue applying roll, a doctor roll co-operating therewith, means for delivering glue to said rolls, and means for substantially enclosing the doctor roll and the lower portion of the glue applying roll comprising a hopper-shaped receptacle disposed below the doctor roll, end walls fixed to said receptacle opposite the end of said roll, cover plates adapted to rest against the edge portions of said end walls to complete the enclosure, and scrapers associated with said end walls, said scrapers extending across the ends of said rolls at the bite thereof.

12. In a machine for applying glue to box blanks, a glue applying roll, a doctor roll co-operating therewith, means for delivering glue to said rolls, and means for substantially enclosing the applying roll comprising a hopper-shaped member disposed below the doctor roll, walls at the ends of the rolls composed of overlapping sections fixed to the hopper, a scraper formed integral with a corresponding section of each end wall, and front and back cover plates adapted to rest on said hopper against the edge portions of the walls, said sections having the scrapers integral therewith being removable without disturbing the rolls or the remaining sections of the end walls.

CUTLER D. KNOWLTON.
